[57] CLAIM

The ornamental design for a car top carrier for transporting building, household and sporting materials, as shown and described.

DESCRIPTION

FIG. 1 is an isometric view of a car top carrier for transporting building, household and sporting materials embodying my new design; and,

FIG. 2 is a side view of the car top carrier for transporting building, household and sporting materials of FIG. 1 mounted on a vehicle roof.

The broken line showing of a car roof and transported material in FIG. 2 of the drawing is for illustrative purposes only and forms no part of the claimed design.

FIG. 1

FIG. 2
